UNITED STATES PATENT OFFICE.

HENRY K. SANDELL, OF CHICAGO, ILLINOIS, ASSIGNOR TO MILLS NOVELTY COMPANY, OF CHICAGO, ILLINOIS, A CORPORATION OF ILLINOIS.

ELECTRIC MOTOR.

1,087,556.

Specification of Letters Patent.

Patented Feb. 17, 1914.

Application filed November 7, 1911. Serial No. 659,054.

To all whom it may concern:

Be it known that I, HENRY K. SANDELL, a citizen of the United States, residing at Chicago, in the county of Cook and State of Illinois, have invented a new and useful Improvement in Electric Motors, of which the following is a specification.

My invention relates to certain new and useful improvements in reciprocatory electric motors, and is fully described and explained in the specification and shown in the accompanying drawings, in which:

Figure 1 is an elevation of a device embodying the invention showing the same in one position; Fig. 2 is a similar view showing the device in another position; Fig. 3 is a side elevation looking at the device of Fig. 1 from the right; Fig. 4 is a view partly in elevation and partly in section of the oscillating armature; Fig. 5 is a circuit diagram of the device in the position shown in Fig. 1, and Fig. 6 is a circuit diagram of the device in the position shown in Fig. 2.

The present device was especially designed in the first instance for operating the bar which raises the dampers of the piano-action in automatic or self-playing pianos, these dampers, as is well understood, being normally held against the strings of the piano by springs or their equivalent. In Figs. 1 and 2, 7 indicates the lower end of one of a series of levers carrying the dampers to be applied to the strings in such a piano. When the loud pedal, or its equivalent in an automatic player, is required, the lower ends of these levers 7 must be pushed backward toward the strings to raise the dampers upon their opposite ends. It may be necessary that all the dampers upon the action be raised or that only a part thereof be raised. In any event the dampers should be raised against the spring action positively, quietly and in certain types of pianos, they must be held raised automatically until released. Hitherto, locking means for holding the dampers raised has been undesirable because of the noise inherent upon the locking operation, and the present device is particularly designed to hold the dampers raised as long as may be required without any operation which may produce noise and to permit them to lower under the action of their springs quietly, yet quickly, when their use is required. Although the motor is specially designed for this use and was, in

fact, constructed in the first instance for this particular purpose, it is evident that there are many other purposes for which it might conveniently be used, and although it is shown in this connection it is not intended in any way to limit its application.

Referring to the drawings, 8 are field-magnets connected by pole-pieces 9, the magnets being so wound and connected, as will be hereinafter explained, that the two ends of the magnets 8 attached to one pole-piece will always be the same polarity, either positive or negative, as the case may be. Thus at all times one pole-piece 9 is necessarily positive and the other negative. Pivoted between the field pole-pieces 9 is an oscillatable armature consisting of a central core 10 terminating in curved shoes 11 of magnetic material and surrounded by the usual coil 12 one terminal of which is grounded upon the frame and the other terminal of which is led out through a central opening 13 in a shaft 14 which supports the armature, so as to make electrical connection with a metal sleeve 15 mounted on the outer end of the shaft 14, but insulated therefrom, and provided with a finger 16.

For clearer understanding of the operation of the device, it may perhaps be stated at this time that the electrical connections, hereafter to be described, are of such character that the current always flows in the same direction in the armature-coil, so that as far as practical operation of the device is concerned, the armature might be a permanent magnet, although manifestly its magnetism can be made more powerful by the use of the electromagnetic construction.

From the foregoing construction, it will be seen that if the parts are in the positions shown in Figs. 1 and 5, and if it be assumed, as indicated in Figs. 5 and 6, that with the particular battery connection the upper end of the swinging armature is positive, then if a current be thrown through the fields in such a direction as to make the left-hand pole-piece of the field positive, the armature will at once swing to the position shown in Fig. 2, where it will remain until another reverse of the poles upon which it will swing in the opposite direction. This is the manner in which the device normally operates to secure the desired results and before proceeding to a description of the electrical-connections where-

by this movement is accomplished, the mechanical connections with the piano-action for which the motor is primarily designed will be set forth.

5 At the rear of the armature is a shaft 17 in line with the shaft 14, and this shaft carries a disk 18 provided with a crank-pin 19 connected by a link 20 with the outer end of an arm 21 extended backward from a 10 damper-raising bar 22 supported by radial extensions 23 hung from a part of the frame of the piano. Thus, when the link 20 is depressed the bar 22 is moved from the position shown in Fig. 1 to that shown in Fig. 2 raising the dampers in an 15 obvious manner. The bar 22 is arranged to contact with felt pieces upon the damper-levers so that the operation of raising the dampers will produce no noise. The 20 crank-pin is so disposed upon the disk 18 that when the armature swings from the position shown in Fig. 1 to that shown in Fig. 2, it will swing past the dead-center thus by the action of the damper springs 25 holding the dampers in a raised position quietly and efficiently, but they can readily be released and lowered by the reversal of polarity in the pole-pieces 9 caused in an obvious manner.

30 In order to secure the electrical changes necessary in the operation of the present device, two actions are necessary, and, from an electrical point of view, the two actions may be performed by separate devices, although the separate devices are united in the preferred form of construction, in the manner hereinafter to be set forth. These separate actions are, first, that upon the movement of the armature from one position to 40 the other, it shall operate a pole-changer, or other equivalent device, so as to reverse the polarity in the field. If this change in polarity alone occurs the armature would immediately move in the reverse direction so 45 that it would perform a constant series of oscillations, but inasmuch as the desired action of the present motor, at least in its preferred construction, is to have the armature swing to one side and remain there until 50 positively returned by controlling mechanism, it is necessary that the armature in addition to changing the polarity of the field shall break the circuit leaving it ready, however, to be closed by controlling mechanism arranged at a distance.

55 24 is a battery, or other source of electric current, one pole of which is by a wire 25 grounded on the frame. The opposite pole is connected by a wire 26 with a switch 27 60 from which the circuit extends in two parallel branches 28 and 29 to contact points 30 and 31 mounted on an insulating block 32.

65 33 and 34 are springs attached to the side of the insulating block 32, said two springs being attached to the two ends of the field-

circuit and terminating in inwardly-projecting tips 35 and 36, either of which may engage with the tip, or finger 16 on the disk 15, carried by the armature-shaft 14, in accordance with the position occupied by the 70 armature. It will be seen that the oscillating finger 16 which moves with the armature, the two springs and the contact points 30 and 31 are analogous in arrangement to a very common form of pole-changer except that instead of a single central piece, the two contacts 30 and 31 are substituted, one of which is connected to each branch of the circuit controlled by the switch. By this means the parts perform the double function, as the armature oscillates, of a pole-changer, and a two-point or cut-off switch adapted to break one branch of the circuit and close the other preparatory to a second operation of the switch 27.

75 Taking the parts, for instance, in the position shown in Fig. 5, if the switch 27 be thrown to the position shown in dotted lines Fig. 5, the current will flow from the positive pole of the battery to the frame of the 90 machine, thence through the armature to the tip 16, thence to the spring 34, through the field to the spring 33, the contact point 31, wire 28 and switch 27 to wire 26 and the battery. The magnetism will be that indicated by the signs in Fig. 5, and manifestly the armature will oscillate to the position shown in Fig. 6. This movement will perform the desired mechanical work, will permit the spring 34 to engage the contact point 95 30 and cause the finger 16 to engage the spring 33, thus reversing the polarity of the field, and by raising the spring 33 from the contact-piece 31 will break that branch of the circuit through which the current has 100 been flowing. If the switch 27 be now thrown in the opposite direction, the current will flow through the armature as before, then through the finger 16 to spring 33, through the field in the opposite direction, to spring 34, contact-point 30, wire 29, switch and the wire 26 back to the battery.

105 It will be seen, as already indicated, that the tip 16, the contact-points 30 and 31 and the springs 33 and 34 are in reality a pole-changer with the added feature of a double contact so that the throw of the pole-changer not only reverses polarity, but breaks one branch of the circuit and closes the other in preparation for the operation 115 120 of the switch. This being true, a number of simple electrical variations will at once occur to any one skilled in the art. In order to maintain the armature of constant polarity the pole-changer must affect only the 125 flow through the field, but this can be done in several ways.

I claim as new and desire to secure by Letters Patent:—

1. A reciprocatory-electric motor, com- 130

prising, in combination, a field magnet, an armature of constant polarity, a single contact-point oscillated by the movement of the armature, two springs adapted to be alternately engaged thereby, two stationary contacts, each adapted to be engaged by that spring which is out of engagement with the oscillatory contact-point, a circuit including two branches, one of which runs to each of the stationary contact-points and a switch controlling the flow of current to said branches.

2. An oscillatory-electric motor, comprising, in combination, a field magnet having field windings, an oscillatory electromagnetic armature, a source of electric current, connections therewith through the armature whereby the armature polarity remains constant, an oscillatory contact-point carried by the armature and in electrical connection with one terminal thereof, two movable springs adapted to be alternately engaged by said oscillatory contact-point, connections between said springs and the field winding, two contact-points, each of which is adapted to be engaged by that spring which is out of engagement with the oscillatory contact-point, two parallel circuit-branches connecting the source of current-supply with said two contact-points, and a switch controlling the flow of current to each branch.

3. An oscillatory-electric motor, comprising, in combination, a field-magnet, an oscillatory armature, a crank-pin carried by the armature and arranged as the armature oscillates from one position to another to swing past the dead center for holding the armature in position, means connected to the crank pin and urging the same in an upward direction, a source of electric-current, means operated by the oscillations of the armature for reversing the polarity of the field, and a circuit, part of which consists of

two branches, and means operated by the oscillation of the armature for breaking one branch and closing the other, and a switch controlling the flow of current through each branch.

4. An oscillatory-electric motor, comprising, in combination, a field magnet, an oscillatory armature of constant polarity, a crank-pin carried by the armature and movable past the dead center to hold the armature in position, means connected to the crank pin and urging the same in an upward direction, an electric-circuit part of which consists of two branches, a switch controlling the flow of current into either branch, and means operated by the movement of the armature for reversing the polarity in the field and breaking one branch of the circuit and closing the other.

5. An oscillatory-electric motor comprising in combination a field-magnet, an oscillatory armature, a crank-pin carried by the armature and arranged as the armature oscillates from one position to another to swing past the dead center for locking the armature in position, means connected to the crank pin and urging the same in an upward direction, a source of current, means operated by the oscillation of the armature for reversing the polarity of one of said magnetic parts, and a circuit part of which consists of two branches, means operated by the oscillation of the armature for breaking one branch and closing the other, and a switch controlling the flow of current through each branch, for the purpose set forth.

In testimony whereof I have hereunto set my hand.

HENRY K. SANDELL.
